UNITED STATES PATENT OFFICE

158,941

MULTIPLE CONDIMENT HOLDER

Adrienne Brita Juvet Dokus and John Ivan
Dokus, Newark, N. J.

Application June 24, 1949, Serial No. 3,506

Term of patent 14 years

(Cl. D44—22)

To all whom it may concern:

Be it known that we, Adrienne Brita Juvet Dokus and John Ivan Dokus, citizens of the United States of America, residing at Newark, in the county of Essex and State of New Jersey, have invented a new, original, and ornamental Design for Multiple Condiment Holder, of which the following is a specification, reference being had to the accompanying drawing, forming a part hereof.

In the drawing:

Fig. 1 is a front perspective view of a multiple condiment holder, showing our new design;

Fig. 2 is a top plan view; and

Fig. 3 is a rear perspective view thereof.

We claim:

The ornamental design for a multiple condiment holder, substantially as shown.

ADRIENNE BRITA JUVET DOKUS.
JOHN IVAN DOKUS.
